[57] CLAIM

The ornamental design for a chassis mounted superstructure carrying frame for soft-top vehicles, as shown and described.

DESCRIPTION

FIG. 1 is a perspective view of a chassis mounted superstructure carrying frame for soft top vehicles showing my new design, the broken lines being for illustrative purposes only;

FIG. 2 is a side elevational view thereof;

FIG. 3 is a front perspective view thereof; and

FIG. 4 is a rear perspective view thereof.

FIG 1

FIG 2
